(57) **CLAIM**

The ornamental design for a point-of-care patient information instrument, as shown and described.

DESCRIPTION

FIG. 1 is a top right perspective view of the point-of-care patient information instrument;

FIG. 2 is a bottom left perspective view of the point-of-care patient information instrument;

FIG. 3 is a right side view, in elevation, of the point-of-care patient information instrument, taken from the frame of reference of FIG. 1;

FIG. 4 is a left side view, in elevation, of the point-of-care patient information instrument, taken from the frame of reference of FIG. 1;

FIG. 5 is a front view, in elevation, of the point-of-care patient information instrument, taken from the frame of reference of FIG. 1;

FIG. 6 is a rear view, in elevation, of the point-of-care patient information instrument, taken from the frame of reference of FIG. 1;

FIG. 7 is a top plan view of the point-of-care patient information instrument, taken from the frame of reference of FIG. 1;

FIG. 8 is a bottom plan view of the point-of-care patient information instrument, taken from the frame of reference of FIG. 1;

FIG. 9 is an exploded top right perspective view of the point-of-care patient information instrument; and,

FIG. 10 is an exploded bottom left perspective view of the point-of-care patient information instrument.

The broken lines depict portions of the point-of-care patient information instrument that form no part of the claimed design.

1 Claim, 10 Drawing Sheets
